(57) CLAIM

The ornamental design for kettle, as shown and described.

DESCRIPTION

FIG. 1 is a side top perspective view of kettle showing our new design;

FIG. 2 is a front view thereof;

FIG. 3 is a rear view thereof;

FIG. 4 is a right view thereof;

FIG. 5 is a left view thereof;

FIG. 6 is a top view thereof;

FIG. 7 is a bottom view thereof; and,

FIG. 8 is a supplementary left view thereof which shows that the spout is opened by gripping the handle of the kettle. The broken line showing of a spout and a grip of the handle in FIG. 8 is for illustrative purpose only and forms no part of the claimed design.
